UNITED STATES PATENT OFFICE.

CARL ADAMS, OF EAST RUTHERFORD, NEW JERSEY.

ELASTIC FABRIC.

1,313,037.

Specification of Letters Patent.

Patented Aug. 12, 1919.

Application filed December 31, 1917. Serial No. 209,711.

To all whom it may concern:

Be it known that I, CARL ADAMS, a citizen of the United States, and a resident of East Rutherford, in the county of Bergen and 5 State of New Jersey, have invented a new and Improved Elastic Fabric, of which the following is a full, clear, and exact description.

The invention relates to woven textile fabrics, and its object is to provide a new and improved elastic fabric capable of expansion and contraction lengthwise without the use of interwoven elastic bands, and which is exceedingly serviceable when manufactured into sweaters, petticoats, and outer or undergarments, surgical bandages and other devices. Another object is to render clothing made of this fabric exceedingly warm and comfortable and capable of yielding 20 with the motions of the body at the same time assuring a snug fit and proper hang of the garments.

In order to accomplish the desired result, use is made of interwoven warp threads, 25 weft threads and connecting or pile warp threads, the said warp threads being crinkled or curled and set to allow the fabric to yield lengthwise, that is, in the direction of the warp threads. Use is also made of an 30 elastic fabric having two parallel weaves each having crinkled or curled warp threads and weft threads interwoven with the said warp threads, and connecting or pile warp threads extending from one weave to the 35 other and interwoven in each weave with the corresponding weft threads thereof.

A practical embodiment of the invention is represented in the accompanying drawings forming a part of this specification, in 40 which similar characters of reference indicate corresponding parts in all the views.

Figure 1 is an enlarged sectional plan view of the fabric after being woven, the section being on the line 1—1 of Fig. 2;

45 Fig. 2 is a sectional side elevation of the fabric on the line 2—2 of Fig. 1;

Fig. 3 is an enlarged sectional plan view of the fabric after being woven, moistened and set to render the fabric elastic length- 50 wise;

Fig. 4 is an enlarged sectional plan view of a modified form of the fabric;

Fig. 5 is a sectional side elevation of another modified form of the fabric; and

55 Fig. 6 is a similar view of another modified form of the fabric.

In producing the elastic fabric two parallel weaves 10 and 11 are simultaneously woven on a suitable loom, each weave having pairs of warp threads 12, 13 and 14, 15, of which the warp threads 12 and 13 of one pair are excessively twisted in one direction while the warp threads 14 and 15 of the adjacent pair are excessively twisted in the opposite direction. The warp threads 12, 13, 14 and 15 are interwoven with weft threads 16 and 17 at the two weaves 10 and 11 and the said weft threads are also interwoven with pairs of connecting warp threads 20, 21 extending diagonally from one weave 65 to the other to connect the weaves 10 and 11 with each other. The weft threads 16 and 17 are interwoven at each weave 10 and 11 alternately with the warp threads 12, 13, 14 and 15, two up and two down for a number of picks, and one up and one down for another number of picks, and the said weft threads are interwoven with the pile warp threads one up and one down at the picks 70 at which the warp threads 12, 13, 14 and 15 are interwoven one up and one down so that each weave is provided with alternately close and loose woven portions, and the said close and loose woven portions of one weave 75 are staggered relative to the close and loose woven portions in the other weave. Thus the portions of each weave at which the connecting warp threads are interwoven are close woven while the adjacent portions which are free of the connecting warp 80 threads are loosely woven. It will also be noticed that a close woven portion of one weave is directly opposite a loose woven portion of the other weave. If desired, the two weaves 10 and 11 after being woven can 85 be separated by cutting the connecting warp threads intermediate the two weaves to form a pile, but I prefer to leave the connecting warp threads uncut to provide a fabric formed of two weaves in the manner de- 90 scribed and in which the connecting warp threads connect the weaves with each other, and the warp threads in each weave are arranged in pairs, of which the warp threads of one pair are excessively twisted in one direction and the warp threads in the adjacent pair are excessively twisted in the opposite direction.

The fabric woven in the manner described is moistened, preferably by the use 110 of steam, to cause the excessively twisted warp threads in the loosely woven portions

of the weaves to crinkle or curl up, as indicated in Fig. 3, and the fabric is next subjected to a finishing action with a view to set the crinkled or curled warp threads and 5 thus to render the fabric elastic lengthwise. The warp threads in the close woven portions of each weave may crinkle or curl up somewhat during the moistening process although the interwoven connecting warp 10 threads tend to prevent such crinkling or curling up. It is understood that on exerting a lengthwise pull in opposite directions on the ends of the fabric, the crinkled or curled and set warp threads tend to 15 straighten out, and when the pressure is released the warp threads tend to curl up again. By the arrangement described the fabric is rendered highly elastic and is capable to yield lengthwise of the warp threads 20 without the use of interwoven elastic bands.

It is expressly understood that the pairs 25 of connecting warp threads 20, 21 are preferably interwoven with the weft threads in one weave through a number of picks and are then extended diagonally across to the other weave and interwoven therein for a number of picks and then returned diagonally to the first weave, and so on throughout the length of the fabric, thus providing 30 alternately close woven and loose woven portions in each weave to permit ready contraction when the fabric is moistened, as previously explained, and the excessively twisted warp threads are caused to crinkle 35 or curl up.

Instead of arranging two pile warp threads between adjacent warp threads in each weave, as shown in Figs. 1, 2 and 3, a single connecting warp thread 30 or 31 is 40 located between adjacent warp threads (see Fig. 4) thus providing a less dense fabric, but otherwise the construction is the same as above described.

In the construction disclosed in Fig. 5, 45 the connecting warp threads 40 and 41 after being interwoven for a number of picks (say three) with the weft threads 42 of one weave pass to the other weave to be interwoven with the next following picks with 50 the weft threads 43 of the other weave, and then the connecting warp threads 40 and 41 extend diagonally across from one weave to the other for a number of picks (say three) and are then interwoven with the corresponding weft threads, as above described.

By this arrangement alternating close and loose woven portions are provided in each weave and with the close woven portion of the two weaves directly opposite each other and the loose woven portions similarly arranged to facilitate the contraction of the warp threads, as above explained.

As shown in Fig. 6, the pair of connecting warp threads 50 and 51 are each interwoven 65 with the weft threads 52 and 53 for a large

number of picks in one weave, and then extended to the other weave and interwoven therein at the next following pick. This fabric is rendered more particularly serviceable with the connecting warp threads cut 70 to provide two separate elastic pile weaves 10 and 11, each for being manufactured into garments, bandages or the like, it being understood that in this case the connecting warp thread in each weave is strongly bound 75 in and is hence not liable to become loose on wearing or brushing the garment.

Although the above described arrangement is the preferred one, a similar result is obtained by excessively twisting the connecting warp threads in the manner set forth, it being understood that in this case the connecting warp threads crinkle and thus provide the desired elasticity without the use of interwoven elastic bands. It is 85 understood that in this case the connecting warp threads are not cut and the two weaves remain united by the excessively twisted, crinkled and set connecting warp threads. From the foregoing it will be seen 90 that the two united weaves are formed of two sets of warp threads of which one set forms a binding warp and the other forms a connecting warp, and one of these sets of warp threads is excessively twisted, crinkled 95 and set to render the fabric elastic lengthwise. It is further understood that the connecting warp threads form pile warp threads in case the double weave fabric is cut to form two individual pile fabrics. 100

It will be noticed that the double weave fabric produced is very serviceable when manufactured into garments as an air space is provided between the two weaves and thus aids in keeping the wearer warm, and the 105 garment material can readily expand and contract to snugly fit the wearer and to allow freedom of the body and limbs thus insuring the utmost comfort.

Having thus described my invention, I 110 claim as new and desire to secure by Letters Patent:

1. An elastic two-ply fabric, comprising two weaves each having interwoven warp threads, weft threads and connecting warp threads, the said warp threads being arranged in pairs and the warp threads of one pair being excessively twisted in one direction, and the warp threads of the adjacent pair being excessively twisted in the 120 opposite direction, the said warp threads being crinkled and set to allow the fabric to yield lengthwise.

2. An elastic two-ply fabric, comprising two parallel weaves each having crinkled 125 and set warp threads, connecting warp threads and weft threads interwoven with the said warp threads and connecting warp threads, the connecting warp threads being interwoven with the weft threads at inter- 130

vals to form alternating close and loose woven portions in each weave.

3. An elastic fabric, comprising two parallel weaves each having crinkled and set 5 warp threads, connecting warp threads and weft threads interwoven with the said warp threads and connecting warp threads, the connecting warp threads being interwoven with the weft threads at intervals to form 10 alternating close and loose woven portions in each weave, the close woven portion of one weave being opposite a loose woven portion of the other weave and vice versa.

4. An elastic fabric, comprising two parallel weaves each having excessively twisted, crinkled and set warp threads, connecting warp threads and weft threads, the weft threads being interwoven with the warp threads of each weave and being interwoven 20 at intervals with the said connecting warp threads whereby each weave is provided with alternating close and loose woven portions.

5. An elastic fabric, comprising two parallel weaves each having excessively twisted, crinkled and set warp threads, connecting warp threads and weft threads, the weft threads being interwoven with the warp threads of each weave two up and two down for a number of picks and one up and 30 one down for a next following number of picks, and being interwoven at intervals with the said connecting warp threads whereby each weave is provided with alternating close and loose woven portions.

35 6. An elastic fabric, comprising two parallel weaves each having excessively twisted, crinkled and set warp threads, connecting warp threads and weft threads, the weft threads being interwoven with the warp 40 threads of each weave to form alternate close and loose portions, the said weft threads being interwoven with the said connecting warp threads at the said close woven portions.

45 7. An elastic fabric, comprising interwoven warp threads, weft threads and connecting warp threads, the said warp threads

being arranged in pairs and the warp threads of one pair being excessively twisted in one direction and the warp 50 threads of the adjacent pair being excessively twisted in the opposite direction, the said warp threads being crinkled and set to allow the fabric to yield lengthwise, the said connecting warp threads being interwoven 55 at intervals with the said weft threads to form alternating close and loose woven portions in each weave.

8. An elastic fabric, comprising two parallel weaves each having interwoven warp 60 threads, weft threads and connecting warp threads, the warp threads in each weave being arranged in pairs, the warp threads of one pair being excessively twisted in one direction and the warp threads in an adjacent 65 pair being excessively twisted in the opposite direction, the said warp threads being crinkled and set to allow the weaves to yield lengthwise, the said connecting warp threads extending diagonally from one 70 weave to the other to connect the weaves with each other and the said connecting warp threads being arranged in pairs interwoven at intervals with the weft threads of each weave to form alternating loose and close 75 woven portions.

9. An elastic two-ply fabric, comprising two parallel weaves each having two sets of warp threads and weft threads interwoven with the said sets of warp threads, 80 one of the said sets of warp threads forming a binding warp and the other a connecting warp extending from one weave to the other, one of the said sets of warp threads having its threads arranged in pairs, the 85 warp threads of one pair being excessively twisted in one direction and the warp threads in an adjacent pair being excessively twisted in the opposite direction, the said pairs of excessively twisted warp threads 90 being crinkled and set to allow the weaves to yield lengthwise.

CARL ADAMS.
